Patented Nov. 26, 1918.

Inventor

Harry D. Garretson
By his Attorney
O. W. Edwards

UNITED STATES PATENT OFFICE.

HARRY D. GARRETSON, OF NEW YORK, N. Y.

INDUCTIVE HIGH-TENSION TERMINAL.

1,285,977.

Specification of Letters Patent. Patented Nov. 26, 1918.

Application filed May 28, 1918. Serial No. 237,027.

To all whom it may concern:

Be it known that I, HARRY D. GARRETSON, a citizen of the United States, and a resident of the city, county, and State of New York, have invented a new and useful Improvement in Inductive High-Tension Terminals, of which the following is a specification.

The object of my invention is to provide a high tension terminal in which is placed an inductive resistance which will prevent any injury to the transformer to which it is attached through undesirable reactions to which such transformer is subjected when in use.

This and other objects are accomplished by my invention, one embodiment of which is hereinafter more particularly set forth.

For a more particular description of my invention, reference is to be had to the accompanying drawing, forming a part hereof, in which:

Figure 1 is a longitudinal section of my high tension, inductive terminal and

Fig. 2 is a sectional view taken on the line 2—2 of Fig. 1, looking in the direction of the arrows.

Throughout the various views of the drawings, similar reference characters designate similar parts.

My improved terminal 1, consists of a hollow body 2 which is provided with the usual

corrugations 3 and screw threads 4, on which may be placed a suitable nut 5, in the conventional manner; so that this insulator can be secured in the usual way to any desired support. The interior of this insulator 1, has a cylindrical bore 6 extending from end to end along its axis and in this bore is mounted a suitable inductive resistance 7 which has its ends secured to bolts 8 with nuts 9 that bear against suitable washers 10 so as to hold this inductive resistance in its proper position.

This inductive resistance 7, when so placed, is protected from all mechanical injury and protects the transformer on to which it is mounted from electrical disturbance or injury as above indicated.

While I have shown and described one embodiment of my invention, it is obvious that it is not restricted thereto, but is broad enough to cover all structures within the scope in the annexed claim.

What I claim is:

In a high tension terminal adapted to protect a transformer, a corrugated insulator with a bore containing an inductive resistance and means for mounting the resistance so that it is protected from all mechanical injury and protects the instrument on which it is mounted from electrical troubles.

HARRY D. GARRETSON.
